[57] CLAIM

We claim the ornamental design for a wide mouth food bottle, as shown and described.

DESCRIPTION

FIG. 1 is a front view of our new design with spoon, with the rear view being identical thereto;

FIG. 2 is a right side view thereof;

FIG. 3 is a left side view thereof;

FIG. 4 is a top view thereof;

FIG. 5 is a bottom view thereof; and,

FIG. 6 is a cross section taking along line 6—6 of FIG. 2; FIG. 7 is a front elevational view of an alternate embodiment of FIG. 1 shown without the spoon, with the rear view being identical thereto;

FIG. 8 is a right side elevational view of FIG. 7, with the left side view being identical;

FIG. 9 is a top plan view of FIG. 7; and,

FIG. 10 is a bottom plan view of FIG. 7.
